GAME BOARD

Virgil Sherman Packard, San Francisco, Calif.

Application March 21, 1952, Serial No. 19,001

Term of patent 14 years

(Cl. D34—5)

To all whom it may concern:

Be it known that I, Virgil Sherman Packard, a citizen of the United States, residing at San Francisco, in the county of San Francisco and State of California, have invented a new, original, and ornamental Design for Game Board, of which the following is a specification, reference being had to the accompanying drawing, forming part thereof.

Figure 1 is a top plan view of a game board showing my new design.

Figure 2 is an edge view of the game board shown in Figure 1.

The bottom side of game board is plain. The shading indicates differences in color only.

The essential features of my new design are shown in full lines.

I claim:

The ornamental design for a game board, as shown and described.

VIRGIL SHERMAN PACKARD.
